UNITED STATES PATENT OFFICE.

WILLIAM S. ELY, OF KATY, TEXAS.

SUPPORT FOR COMPASSES.

1,008,803.

Specification of Letters Patent. Patented Nov. 14, 1911.

Application filed October 7, 1910. Serial No. 585,853.

To all whom it may concern:

Be it known that I, WILLIAM S. ELY, a citizen of the United States, residing at Katy, in the county of Harris and State of Texas, have invented new and useful Improvements in Supports for Compasses, of which the following is a specification.

This invention relates to improvements in casings or supports for compasses primarily intended for use for railway coaches, and the object of the invention is to provide a device of this character which may be suspended from the top of the coach and whereby the direction of travel may be readily discernible by the passengers without the necessity of the passengers leaving their seats.

With the above, and other objects in view, which will appear as the description progresses, the invention resides in the novel construction and combination of parts hereinafter fully described and claimed.

In the accompanying drawings, Figure 1 is a side elevation of the improved compass support and compass, showing the same attached to the ceiling of an ordinary railway coach the latter being shown in cross section. Fig. 2 is a central longitudinal sectional view through the support. Fig. 3 is a top plan view of the compass support.

In the drawings, 1 designates an ordinary railroad coach, and 2 the top thereof.

The numeral 3 designates a bracket which is suspended from the top 2. This bracket comprises a central portion formed with an upstanding threaded ring 4, and from which is extended in opposite directions the supporting arms 5 and 6. These arms 5 and 6 are curved upwardly and have their extremities forked to provide diverging branches 7 and 8. The branches have their extremities perforated for the reception of securing elements 9 whereby the device is suspended from the top 2 of the coach. The central portion of the device, adjacent the ring 4, has its ledge formed with a plurality of openings 10, the said openings registering with similar openings formed in the base 11 of a needle supporting member 12. The openings are adapted to receive suitable securing elements 11', such as small nuts and bolts, as shown in Fig. 2 of the drawing. The member 12 is provided with a centrally arranged standard 12', which is integrally connected with the base 11, and the standard has its upper portion formed with a right angularly disposed substantially U-

shaped member 12", the latter adapted to serve as a guard for a magnetic needle 12", which is supported upon the pin extension 12" provided upon the top of the standard 12'. The central portion of the needle 12" is formed with a substantially cone shaped pocket 12", and the pocket is adapted to receive the pointed extremity of the pin 12".

The numeral 13 designates a casing for the needle and its support. This casing 13 is constructed of some transparent material, such as glass, to provide means whereby the needle 12" is visible to the occupants of the seats of the coach. The casing 13 preferably comprises a cylindrical member having both its ends open, and its lower end formed with threads adapted to coact with the threads upon the ring 4 of the bracket. The upper threaded end of the casing 13 is adapted to receive threads of the flanged threaded portion of a removable cap 15. The central portion of the bracket or the exterior of the transparent casing 13 may be provided with marks indicating the points of the boxing of the compass, so that the passengers of the coach may readily ascertain the direction in which the train is traveling.

Having thus fully described the said invention, what I claim is:

1. In a device for the purpose set forth, a bracket having a central ring portion, and oppositely disposed arms, said arms having their extremities forked, the forked members having openings adapted to receive securing elements, a support connected with the central portion of the bracket, a magnetic needle loosely mounted upon the support, and a transparent casing surrounding the needle and support and engaging with the ring of the bracket.

2. In a device for the purpose set forth, a bracket having its central portion provided with a ring, said bracket being formed with oppositely disposed arms having their extremities forked, the ends of the forked members being formed with openings adapted to receive securing elements, a needle support connected with the bracket, said support comprising a base, a standard, a U-shaped guard arranged at an angle to the support and a projecting pin, a magnetic needle arranged between the arms of the guard, said needle having its central portion formed with a cone shaped depression engaging with the pointed end of the pin, a

transparent casing, said casing having both of its ends open and threaded, one of the said threaded ends adapted to engage with the threaded ring, and a cap having a 5 threaded flange adapted to engage the upper open end of the casing.

3. In a device for the purpose set forth, a bracket having a central ring member and oppositely disposed arms having openings 10 for the reception of securing elements, and

a member carrying a compass arranged within the ring when the device is secured in position for use, the needle of the said compass being above the ring.

In testimony whereof I affix my signature 15 in presence of two witnesses.

WILLIAM S. ELY.
